Des. 1506

John Holt, of Gardner, Maine,
No. 1506. Letters Pat. No. 141, dated Dec. 10, 1861.

The schedule is referred to in these Letters Patent and making part of the same.

To all whom it may concern:

Be it known that I, John Holt, of Gardner, in the County of Kennebec and State of Maine, have invented or produced a new and original Design for a Rolling Pin, and I do hereby declare the following to be a full, clear and exact description of the same, reference being had to the accompanying drawings making a part of this specification in which -

Figure 1. is a front view of a rolling pin showing my design.

Figure 2. is a transverse section of the pin, taken at the line X-X .

Similar letters of reference indicate corresponding parts in the two figures.

The object of this invention is to produce a new and ornamental design for a rolling pin for marking gingerbread and other pastry.

To enable others to fully understand my invention I will proceed to describe it.

The configuration of the two outer spaces C-D. of the rolling pin is precisely the same in both and consists of six V. shaped grooves extending circumferentially around the pin. The periphery of the right hand middle space E, or space at the right hand of the centre cutter, is made a trifle concave and has a representation of foliage cut into the surface thereof, and extending about two thirds of the distance around the same.

On each side of the said Figure are two V. shaped grooves extending entirely around the pin the outer of the said grooves or those adjacent to the face of the cutters being made a little larger than the inner grooves.

The left hand middle space F, or space at the left hand side of the centre cutter has stamped or cut in its surface two shields with their broad ends placed towards each other and nearly together, with scroll

Res. 1506

work placed between and at right angles thereto.

Having thus described my invention, what I claim as new and desire to secure by Letters Patent, is —

The general configuration of parts herein shown and described, to form a new and original design for a Rolling Pin.

Witnesses,

George W. Smith.

A. J. Parker.
